UNITED STATES PATENT OFFICE

EMILE CORNIC, OF PARIS, FRANCE

UMBRELLA

Application filed December 11, 1930, Serial No. 501,631, and in France June 18, 1930.

The present invention has for object improvements in the assemblage of umbrellas, referring more particularly to a device for holding the ribs stationary in the closed position.

According to the invention, the nut usually secured at the end of the stem, and on which the ribs are pivoted, is slidably mounted and a suitable resilient device constantly urges 10 towards the opposite end of the stem the structure constituted by the nut and the ribs, thus causing the end of the ribs to enter a cup mounted on the handle when the umbrella is closed.

The tension of the above mentioned resilient member automatically holds the umbrella in this position, whilst in the existing devices, which are usually provided with a cup sliding on the handle, the ribs can easily 20 slip out of the said cup; moreover, the frequent sliding of the cup rapidly damages this handle. Finally, the fixed cup is quite independent of the size and shape of the handle, whilst the sliding cup was necessarily 25 related to this size and shape, which practically rendered it unapplicable to ladies' umbrellas.

Another advantage resulting from the resilient mounting of the nut carrying the ribs, 30 consists in that the covering fabric is not liable to be subjected to excessive stresses when the umbrella is opened to its full extent, which frequently happens with the ordinary rigid mounting when the size of this fabric is slightly insufficient.

On the other hand, owing to the fact that the cup is fixed, the assemblage of the umbrella on its stem as well as the securing in position of the arm-knot or arm-strap include appreciable simplifications consisting 40 in that the arm-knot or arm-strap is secured to the stem by a ring to which it is connected, and which may either be previously assembled with the cup by beading or otherwise, or 45 held in place by clamping between a shoulder of the said stem and the base of the handle mounted on the latter. The ring is therefore firmly held without having to employ any of the standard assembling devices.

50 The accompanying drawings illustrate, by

way of example, an umbrella according to the invention, the fabric being removed.

Fig. 1 is an elevation with axial sections according to the axis.

Fig. 2 is a cross section on line II—II of 55 Fig. 1.

For simplification, the inner branches and the movable nut serving to move the ribs through the medium of the said branches have not been shown, as these usual members 60 present no particularity.

The nut 1, on which the ribs 2 are attached by a wire 3 in the usual manner, is slidably mounted on a short sleeve 4 secured about a tenon 5 provided at the end of the stem. 65

A spring 6 is interposed between the sleeve 4 and the nut 1 and bears, on the one hand, on a flange 7 carried by the end of the sleeve 4 and, on the other hand, on a ledge 1a integral with the nut. This spring, which is a 70 compression spring, constantly returns the nut and ribs towards the opposite end of the stem; their displacement is limited by the shoulder 8 of the stem.

On the other hand, a cup 9 is mounted on a 75 reduced portion of the handle, so that it can fit over or cover the tips of the ribs. This cup is held, for instance, by a cap 10 secured on the reduced end of the handle. The relative arrangement of these various members is 80 such that in closed position, the spring 6 pushes the ribs 2, so that the ends of the latter enter the cup 9 and are held therein.

The nut 1 is rigid with the socket 12 which 85 covers the spring 6 and the end of the stem and which can only longitudinally slide relatively to the latter, the relative rotation of these parts being prevented by ribs 13 of the socket 12 which extend in notches of the flange 7. 90

A cap or cover 15 secured to the socket 12 protects and conceals the device thus arranged.

This guide device serving to prevent the ribs from rotating about the stem, is shown 95 by way of example only and could be replaced by any other suitable device.

The umbrella being closed, it suffices, for opening it, to exert a slight pull on the handle and on the ribs, so as to compress the spring 100

and to release the end of the latter. The same operation effected when shutting the umbrella, allows of bringing the ribs against the stem; the spring expands when the handle is no longer pulled upon and the cup 9 covers and holds the ribs.

On the other hand, the arm-knot or arm-strap 16 of the umbrella is mounted in the following manner: this arm-strap is secured 10 to a washer 17, for instance by means of rings 18, 19 carried by these two parts. The washer 17 can be held on the handle between the shoulder of the latter and the bottom of the cup 9.

15 In case the handle is removable, its withdrawal allows of instantaneously removing the washer 17 and the arm-strap as well as the cup 9.

It is to be understood that the invention is 20 not limited to the form of construction above described solely by way of example and that, without departing from the said invention, the shape and arrangement of these constituent parts might be modified in any suitable 25 manner; the nut 1 and its returning device might be mounted on the stem in any other manner than that illustrated, the washer 17 and cup 9 might be left independent as shown, or they might be assembled for instance by 30 beading, or they might again be connected in one piece by pressing, and the handle might be of any shape and mounted on the stem by any other method than those shown. Finally, the cup might be provided in the base 35 itself of the handle; it can be given a polygonal shape, having for instance as many apices as there are ribs, etc.

Claims:

1. Umbrella comprising a stem the end of 40 which opposite to the handle has a reduced portion and a shoulder, a sleeve secured on the said reduced portion and having a flange at its outer end, a nut slidably mounted on the said sleeve and having an inner ledge, a 45 spring about this sleeve and compressed between the flange of the latter and the inner ledge of the said nut, a movable cap covering the said spring and the said sleeve and connected to the said sliding nut, and ribs 50 pivoted on the said sliding nut.

2. Umbrella comprising a stem the end of 55 which opposite to the handle has a reduced portion and a shoulder, a sleeve secured on the said reduced portion and having a flange at its outer end, a nut slidably mounted on the said sleeve and having an inner ledge, a 60 spring about the said sleeve and compressed between the flange of the latter and the inner ledge of the said nut, a movable cap covering the said spring and the said sleeve and connected to the said sliding nut, and ribs pivoted on the said sliding nut, the latter being guided on the said sleeve so that it cannot rotate about the same.

65 3. Umbrella comprising a stem the end of

which opposite to the handle has a reduced portion and a shoulder, a sleeve secured on the said reduced portion and having a flange at its outer end, a nut slidably mounted on the said sleeve and having an inner ledge, a 70 spring about the said sleeve and compressed between the flange of the latter and the inner ledge of the said nut, a movable cap covering the said spring and the said sleeve and connected to the said sliding nut, ribs pivoted on the said sliding nut, the latter being guided on the said sleeve so that it cannot rotate about the same, and a cup adapted to receive the free ends of the ribs when the umbrella is shut, the said cup being fixed in the axial direction.

75 In testimony whereof I have hereunto affixed my signature.

EMILE CORNIC.
